THERMOSTAT HOUSING

John J. Hughes, Jr., and Clifford Brooks Stevens,
Milwaukee, Wis., assignors to Milwaukee Gas
Specialty Company, Milwaukee, Wis., a corpo-
ration of Wisconsin

Application February 6, 1951, Serial No. 14,113

Term of patent 14 years

(Cl. D52—7)

To all whom it may concern:

Be it known that we, John J. Hughes, Jr., and Clifford Brooks Stevens, both citizens of the United States and residing at Milwaukee, in the county of Milwaukee and State of Wisconsin, have invented a new, original, and ornamental Design for Thermostat Housing, of which the following is a specification, reference being had to the accompanying drawing, forming a part thereof.

In the drawing:

Figure 1 is a perspective view of a thermostat housing embodying our new design, looking downwardly from one end; and

Figure 2 is a perspective view of the thermostat housing shown in Figure 1, looking upwardly from the opposite end.

We claim:

The ornamental design for a thermostat hous-
ing, substantially as shown.

JOHN J. HUGHES, JR.
CLIFFORD BROOKS STEVENS.
